UNITED STATES PATENT OFFICE.

ERASTUS DE MOULIN, OF GREENVILLE, ILLINOIS, ASSIGNOR TO DE MOULIN BROS. & CO., OF GREENVILLE, ILLINOIS.

TRICK-GUN.

No. 893,573.

Specification of Letters Patent.

Patented July 14, 1908.

Application filed December 9, 1907. Serial No. 405,774.

To all whom it may concern:

Be it known that I, ERASTUS DE MOULIN, a citizen of the United States, residing at Greenville, in the county of Bond and State of Illinois, have invented a new and useful Trick-Gun, of which the following is a specification.

This invention relates to trick guns of that general class especially designed for use by 10 the members of lodges, fraternities, secret orders and similar organizations for initiating candidates.

The object of the invention is to provide means whereby an ordinary air rifle may be 15 converted into a water gun without the employment of additional operating mechanism and without altering the general appearance of the rifle.

A further object of the invention is to provide 20 a trick gun or rifle having a forward and rearward discharge whereby liquid or other projectable substance may be ejected from either end of the gun.

A further object is to provide a rearwardly 25 extended discharge passage or barrel communicating with the fluid receiving chamber and controlled by a suitable valve or stop cock, there being a similar valve for controlling the discharge of fluid at the muzzle 30 of the gun so that by manipulating said valves the direction of discharge of fluid may be changed at will.

A still further object of the invention is generally to improve this class of devices so 35 as to increase their utility, durability and efficiency.

Further objects and advantages will appear in the following description, it being understood that various changes in form, 40 proportions and minor details of construction may be resorted to within the scope of the appended claims.

In the accompanying drawings forming a part of this specification: Figure 1 is a longitudinal sectional view of a trick gun constructed in accordance with my invention. Fig. 2 is a side elevation of the same. Fig. 3 is a transverse sectional view taken on the line 3—3 of Fig. 1. Fig. 4 is a similar view 50 taken on the line 4—4 of Fig. 1. Fig. 5 is a detail perspective view of a portion of the rearward discharge tube or barrel.

Similar numerals of reference indicate corresponding parts in all of the figures of the 55 drawings.

The improved device is in the nature of an attachment to an air rifle whereby the latter may be used as a water gun, and by way of illustration is shown applied to a "Daisy" air rifle of the ordinary construction in which 60 5 designates the casing or housing, 6 the stock and 7 the false barrel.

As a description of the air rifle when used as such is essential to the proper understanding of the same when converted into a water 65 gun the several parts will be specifically designated and referred to in the specification.

Disposed within the false barrel 7 is the usual transverse partition 8 dividing the barrel into two compartments 9 and 10 one of which constitutes a fluid containing compartment and the other a chamber for the reception of the plunger 11, the chamber 10 also serving to receive the water from the 75 compartment 9 when the plunger is retracted and the rifle used as a water gun.

The partition 8 is provided with a central perforation the walls of which are threaded for connection with a sleeve or collar 11, 80 and detachably secured to said collar and spaced from the interior walls of the false barrel 7 is the true barrel 12. A spring 8' is secured to the true barrel 12 with its free end normally closing a filling orifice 9' in the 85 false barrel 7, this orifice being employed to permit the introduction of a quantity of shot into the chamber 9 when the device is used as an air gun. The free end of the barrel 12 is soldered or otherwise rigidly secured to a terminal cap 13 removably seated in the adjacent end of the barrel 7 so that by rotating the cap the barrel 12 may be unscrewed from the partition 8 and said barrel and cap disconnected from the false barrel 90 7 when it is desired to fill the containing chamber with water or other liquid.

The spring actuated plunger 11 is slidably mounted for longitudinal movement within the chamber 10 and is provided at one end 100 thereof with a terminal roller 14 for engagement with the usual operating lever 15, it being here stated that when the plunger is retracted the water in the compartment 9 will be drawn into the receiving chamber 10 105 and forcibly ejected from said receiving chamber when the plunger is released, in the manner hereinafter described.

The several parts above referred to are of the usual construction, the present invention 110

residing in means whereby the gun may be filled with water and the latter discharged through either end of said gun.

Disposed within the free end of the barrel 5 or passage 12 is a tubular member or plug 16 having a discharge orifice 17 formed therein and intersected by a transverse opening 18, the walls of which are threaded for engagement with a valve 19 preferably in the form 10 of a screw, as shown.

The false barrel 7 is provided with a depending enlargement 20 to which is secured a rearwardly extending discharge tube or auxiliary barrel 21, the latter being preferably 15 extended along one side of the casing or housing 5 and having its discharge end deflected upwardly so as to assist in preventing the water from escaping through said tube until the valve 22 is opened and the plunger 20 actuated.

The discharge passage 21 communicates with the receiving chamber 10 through the medium of a vertically disposed opening 23 formed in the enlargement 20 and in which 25 is seated the valve or screw 22 whereby the passage of fluid through the discharge 21g may be controlled at will.

In operation the cap 13 carrying the barrel 12 is removed by rotating the same and a 30 small quantity of water introduced into the compartment 9 through the open end of the barrel 7, after which the plunger is retracted by manipulating the lever 15 in the usual manner thus causing the fluid in the compartment 9 to enter the chamber 10 through the opening in the partition 8 and partially fill said chamber.

If a forward discharge is desired the valve 22 is closed and the valve 19 moved to open 40 position after which the barrel 12 and cap 13 are inserted in the barrel 7 and the trigger 24 actuated to discharge the gun thereby causing the fluid in the receiving chamber 10 to be forcibly ejected through the discharge 45 orifice 17 in the form of a small stream.

In order to effect a rearward discharge the valve 19 is closed and the valve 22 moved to open position so that when the plunger is retracted and the trigger operated the liquid 50 will be discharged through the passage 21 in the face of the operator.

Attention is called to the fact that the valve 19 is effectually housed within the false barrel 7 thus giving the device the general appearance of an ordinary air rifle or gun.

In using the gun for initiating purposes the candidate is told that his confidence in the "Order" is to be tested by having one of the members act as William Tell and shoot the 60 apple from his head. The apple is placed on the head of the candidate and he is commanded to stand perfectly still. The member using the rifle or gun adjusts the latter so as to produce a forward discharge with the 65 result that the candidate gets the discharge

of water in his face. He is then handed the gun and given the privilege of acting the part of William Tell and is to shoot the apple from the head of another supposed candidate, the valves of the rifle having been previously adjusted, so that when the candidate fires the gun he will receive another discharge of water in his face.

While it is preferred to use a single gun capable of discharging fluid through either end thereof it is obvious, and sometimes desirable, that the guns may be used in pairs, that is to say with one of the guns having a forward discharge and the other a rearward discharge so that the same result may be accomplished without the necessity of adjusting the valves or changing the guns. It will also be understood that any suitable powdered material such as flour may be used as a charge in place of water if desired.

From the foregoing description it is thought that the construction and operation of the device will be readily understood by those skilled in the art and further description thereof is deemed unnecessary.

Having thus described the invention what is claimed is:

1. A trick gun having front and rear discharge passages and means for discharging a projectable substance through either passage.
2. A trick gun having front discharge and rear discharge barrels, and valves one operating in each barrel for controlling the discharge of a projectable substance through each barrel.
3. A trick gun having a chamber adapted to receive a projectable substance and provided with forward discharge and rearward discharge barrels communicating with said chamber, and separate means for controlling the discharge of the projectable substance through each barrel.
4. A trick gun including a chamber adapted to receive a projectable substance, a plunger operating within the chamber, forward and rearward discharge barrels communicating with said chamber, and separate valves for controlling the discharge of the projectable substance through each barrel.
5. A trick gun including a false barrel provided with a fluid receiving chamber, a plunger operating within said chamber, a true barrel arranged within the false barrel and spaced from the interior walls thereof, said true barrel being in communication with the chamber, a tubular member inserted in one end of the true barrel, and a valve operating within the tubular member for controlling the discharge of fluid through said barrel.
6. A trick gun including a false barrel provided with a fluid receiving chamber, a plunger operated within said chamber, a true barrel arranged within the false barrel and spaced from the interior walls thereof and

communicating with the receiving chamber, a rearwardly extending barrel opening into the receiving chamber, means for operating the plunger, means for controlling the discharge of fluid through the rearwardly extending barrel, and means for controlling the discharge through the true barrel.

7. A trick gun including forward discharge and rearward discharge barrels, a chamber communicating with said barrels and adapted to receive a projectable substance, a plunger operating within the chamber, a tubular member seated in one end of the forward discharge barrel, a valve operating within the tubular member for controlling the discharge of the projectable substance through said tubular member, and a valve for controlling the discharge through the rear barrel.

20 8. A trick gun including a false barrel provided with a transverse partition dividing the false barrel into spaced chambers, a true barrel disposed within the false barrel and communicating with one of said chambers, a 25 plunger operating within said chamber, a rear discharge barrel communicating with the plunger receiving chamber, and separate valves operating within the true barrel and rear discharge barrel for controlling the discharge of a projectable substance through 30 either barrel.

9. A trick gun including a chamber adapted to receive a projectable substance, a plunger operating within the chamber, forward discharge and rearward discharge barrels 35 communicating with said receiving chamber, and a valve operating within each barrel for controlling the discharge of the projectable substance through the same, the rearward barrel being inclined upwardly and extended 40 to a point adjacent the stock of the gun.

10. A trick gun including a forward discharge barrel, a chamber communicating with said barrel and adapted to receive a projectable substance, a plunger operating within the chamber, a rear barrel communicating with said chamber and having its discharge end inclined upwardly, and a valve for controlling the passage of the projectable substance through the rear barrel.

45 11. A trick gun having a plurality of passages leading in different directions, and means for discharging a projectable substance through either passage.

50 In testimony that I claim the foregoing as my own, I have hereto affixed my signature in the presence of two witnesses.

ERASTUS DE MOULIN.
